UNITED STATES PATENT OFFICE.

HERBERT W. WOLFF, OF ST. LOUIS, MISSOURI, ASSIGNOR TO AMERICAN CAR AND FOUNDRY COMPANY, OF ST. LOUIS, MISSOURI, A CORPORATION OF NEW JERSEY.

CAR-UNDERFRAME.

1,021,123.

Specification of Letters Patent. Patented Mar. 26, 1912.

Application filed April 9, 1909. Serial No. 488,912.

To all whom it may concern:

Be it known that I, HERBERT W. WOLFF, residing at St. Louis, Missouri, and being a citizen of the United States, have invented 5 certain new and useful Improvements in Car-Underframes, of which the following is a full, clear, and exact description, such as will enable others skilled in the art to which it appertains to make and use the same, 10 reference being had to the accompanying drawings, which illustrate the preferred form of the invention, though it is to be understood that the invention is not limited to the exact details of construction shown 15 and described, as it is obvious that various modifications thereof will occur to persons skilled in the art.

In said drawings: Figure 1 is a plan view of one end of a car underframe provided 20 with the invention. Fig. 2 is a relatively central longitudinal section the section being taken on line 2—2 of Fig. 1. Fig. 3 is a transverse section taken back of one of the cross bearers or needle beams on line 3—3 25 of Fig. 1. Fig. 4 is a transverse section of Fig. 1 taken on line 4—4 looking toward the bolster. Fig. 5 is an end elevational view showing the end sill and slotted center sill. Fig. 6 is a fragmentary and enlarged 30 plan view of the end portion of the center sill showing its connection with the end sill and the bolster. Fig. 7 is a fragmentary enlarged section the section being taken on line 7—7 of Fig. 1. Fig. 8 is a transverse 35 sectional view on the line 8—8 of Fig. 2, the parts being considerably enlarged. Fig. 9 is a detail fragmentary side elevation, the cross-bearer being seen in end elevation.

Referring to the parts, 1 is a single rolled 40 center sill member either an I-beam or an H section which is placed with its web 2 vertically disposed and with its upper and lower flanges 3—4 horizontally disposed, the sill being slotted in different places along its 45 length as hereinafter pointed out, while the end portion is slotted longitudinally so as to receive in the slotted portion a draft rigging not shown.

5—5 are the end sills which are of considerably less depth than said center sill, the lower flange of the channel end sill 5 being in alinement with the upper edge of

the slot cut longitudinally in the center sill. In this construction it has been sought to avoid weakening the center sill to any considerable extent because of enlarged openings in the web portion thereof and to that end the built up body bolsters shown in elevation in Fig. 4 and in section in Fig. 7 are provided with pressed and flanged dia- 60 phragms 6 whose inner vertical flanges 7 are connected by rivets which extend continuously through said flanges 7 and through the intervening web 2 of the center sill, thereby providing closely juxtaposed bolster dia- 65 phragms which are in fact connected by a direct connecting means, the means in the present instance comprising the rivets 8.

The bolster diaphragms are also provided with flanges 9 which extend along the entire 70 bottom side of said diaphragms and flanges 10, which extend from the vertical flanges 7 outwardly practically to the ends of said diaphragms 6. The bottom flanges 9 rest upon the outstanding flanges 4 of the center sill and are riveted to said flanges by vertically disposed rivets 11, as best shown in Figs. 4 and 7. A bottom bolster cover plate 12 is provided, which extends continuously practically from end to end of the 75 bolster and is riveted to the outstanding bottom flanges of the bolster diaphragms as well as to the outstanding bottom flanges 4 of the center sill. A top bolster cover plate 13 is riveted to the top flanges 10 of 80 the bolster diaphragms and extends longitudinally of the bolsters some little distance below the top flanges 3 of the center sill, this cover plate extending continuously from end to end of bolster in the preferred con- 85 struction, the center sills being reinforced by heavy angles 14 secured by suitable rivets to the web of the center sill above the bolster cover plate 13 and by vertical rivets through the horizontal legs of said angles 14 90 to bolster cover plate 13 and the outstanding flanges 10 along the upper side of the bolster diaphragms.

It is to be understood that the bolster is provided with relatively parallel dia- 100 phragms 6 with outstanding flanges, as shown in the sectional view Fig. 7, and the rivets 8 before referred to are provided to connect the diaphragms which are in aline-

ment, there being two rows of said rivets 8 at each bolster.

The crossbearers or needle beams comprise the horizontal angles 16 which extend 5 through relatively triangular openings or slots 17 in the webs of the center sill and extend continuously outwardly below the horizontal web of the side connecting member, which is provided with inner vertical 10 flange 18 and outer depending flange 19, rivets 20 extending through the horizontal leg of the angles 16 and the horizontal web of the Z shaped side connecting member while rivets 21 extend horizontally through the 15 vertical leg 19 of said Z shaped side connecting member and through angular connecting members 22 by means of which said Z shaped member is secured to the crossbearers or needle beams. The lower angles 20 23 of said crossbearers extends through triangular openings 17' in said web 2 of the center sill and are connected with the upper angles by means of rivets passing through the overlapping vertical legs of the angles 25 16—23 by means of plates 25 riveted to both and by means of angular web connected plates 26, which latter have flanges riveted through the vertical legs of the angles 16—23 and to the web of said center sill. The 30 plates 26 extend above the angles 16 of the cross bearers so as to afford a sufficient connection to the center sill web. Secured to the inner faces of the end sills are angles 30 connected with which are diagonal braces 35 31 which extend rearwardly and outwardly and are connected with the horizontal web of the side connection members, as best shown in plan view Fig. 1.

It will be noted that the top bolster cover 40 plate 13 is turned up at its outer ends, as best shown in Fig. 4 and is riveted to the inner vertical leg 18 of the Z shaped side member. This Z shaped side member is not a sill in the sense that the word sill is used 45 to indicate a principal carrying member of an underframe, but serves as a support for the wood nailing strips 32 and connects the outer ends of the end sill, bolsters and cross bearers or needle beams so as to stiffen the 50 underframe and by means of the other connections shown to throw the load inwardly to the center sill. The body bolsters, as shown in Fig. 4, are provided with side bearings 33 while vertical stiffening members 34 55 extend between the top and bottom diaphragm flanges so as to stiffen the bolster at those points.

What I claim is:

1. In a car underframe, the combination 60 comprising end sills, a single rolled center sill extending from end sill to end sill, vertically flanged side connecting members in the planes of the center sill, a bolster comprising a pair of spaced members upon each 65 side of said center sill extending from the

web of the center sill to the side connecting members and being fixed to said center sill and to said side connecting members, and diagonal braces connecting the end sills with the webs of said side connecting members 70 being fixed to said end sills intermediate said center sill and side connecting members.

2. In a car underframe, the combination comprising end sills, a single rolled center sill in the median line of said underframe 75 and side connection members each extending from end sill to end sill, built up bolsters, cross bearers comprising top and bottom angles passing through said center sill, and means upon opposite sides of said center sill 80 for connecting said top and bottom angles, said connecting means being joined together by rivets through said center sill.

3. In a car underframe, the combination comprising end sills, a single rolled and flanged center sill extending longitudinally of said underframe along the median line thereof, side connection members extending from end sill to end sill, cross bearers comprising upper and lower angles extending 90 through the web of said center sill, and flanged connection plates upon opposite sides of said center sill riveted together through said center sill and fixed to a flange of each 95 of said angles.

4. In a car underframe, the combination comprising end sills, a single rolled and flanged center sill, side connection members extending from end sill to end sill, cross bearers comprising upper and lower angles 100 extending through the web of said center sill, and means connecting said angles with the center sill web, said angles being lapped and connected together at their ends.

5. In a car underframe, the combination 105 comprising end sills, a single rolled and flanged center sill, side connection members extending from end sill to end sill, and cross bearers comprising upper and lower angles 110 extending through the web of said center sill, said angles being lapped and riveted together at their opposite ends.

6. In a car underframe, the combination comprising end sills, a single rolled and flanged center sill, side connection members 115 extending from end sill to end sill, and cross bearers comprising upper and lower angles extending through the web of said center sill, one of said angles being straight from end to end and the other of said angles being 120 bent at opposite sides of said center sill and having its ends lapping the ends of the first angle and fixed thereto and to the side connection members.

7. In a car underframe a single center sill 125 extending longitudinally of said underframe along the median line thereof a built up bolster with integral inner flanges which are connected at each side of said center sill by rivets extending through the web of said 130

- sill and through the flanges, and a cover plate of said bolster extending through said center sill.
8. In a car underframe a single rolled center sill having top flanges and depending web, a bolster comprising a plurality of diaphragms having integral flanges secured to the web of said center sill by rivets extending through said sill web and through a plurality of the diaphragm flanges, a bolster cover plate, and means connecting said cover plate to said center sill above said cover plate.
9. In a car underframe, a single web center sill with top and bottom flanges extending longitudinally of the underframe along the median line thereof in combination with a plurality of integrally flanged bolster diaphragms connected with said web by single rivets extending through said sill web and through a plurality of diaphragm flanges, and a cover plate for said diaphragms extending through said center sill.
10. An underframe for cars comprising suitable end sills, body bolsters, and a center sill consisting of a single rolled metal beam extending continuously from end to end of the car past said bolsters to points adjacent to said end sills and connected thereto, said bolster comprising integrally flanged diaphragms resting on said center sill and riveted together through the web of said sill, a bolster cover plate, and means fixed to the upper surface of said cover plate and to the web of said center sill.
11. An underframe for cars comprising suitable end sills, body bolsters, and a center sill consisting of a single rolled metal I-beam extending continuously from end to end of the car past said bolsters to points adjacent to said end sills, said bolster comprising flanged diaphragms riveted to the lower flanges of said center sill and to its web portion, and a top cover plate formed with upstanding portions fixed to said center sill.
12. An underframe for cars comprising suitable end sills, body bolsters, and a center sill consisting of a single rolled metal beam extending continuously from end to end of the car past said bolsters to points adjacent to said end sills, said bolster being of less height than said center sill and comprising a pair of integrally flanged diaphragms on each side of said center sill those on one side being secured to those on the opposite side by rivets passing through the web of said sill and through the diaphragm flanges, and a top cover plate formed with upstanding portions fixed to said center sill.
13. An underframe for cars comprising suitable end sills, body bolsters, and a center sill consisting of a single rolled metal beam of greater depth than said end sills and extending continuously from end to end of the car past said bolsters to points adjacent to the same and having vertically spaced openings between its upper and lower edges, cross bearers extending through some of said openings and built up bolsters extending through others of said openings, said bolsters comprising flanged diaphragms riveted together through the web of said center sill and resting on the lower flanges of said center sill.
14. An underframe for cars comprising suitable end sills, body bolsters and a center sill consisting of a single rolled metal beam extending continuously from end to end of the car along the median line thereof to points adjacent to said end sills and having longitudinally elongated openings in its ends, in combination with a bolster comprising flanged diaphragms riveted together through said center sill web, and a top cover plate extending through said center sill and riveted to said diaphragms.
15. In a car underframe, the combination comprising end sills, a single rolled main longitudinal carrying member having longitudinally extending slots in the end portions, a plurality of bolster diaphragms on opposite sides of and of less height than said carrying member, flanged horizontally arranged reinforcing members on opposite sides of the carrying member and connected thereto, a slot in said carrying member arranged between the bolster diaphragms, a continuous bolster top cover plate extending through said slot and connected to said reinforcing members and to upper flanges of the bolster diaphragms, and angle members fixed to said cover plate and to said carrying member above said cover plate.
16. In a car underframe, the combination comprising end sills, side connecting members, a single rolled center sill, and a built-up bolster connecting the web of the center sill to the side connecting members and comprising a top cover plate formed with upstanding portions fixed to said center sill.
17. In a car underframe, the combination comprising a single rolled center sill extending longitudinally of said underframe along the median line thereof, and a cross-bearer having top and bottom stress members extending through the web of the center sill.
18. In a car underframe, the combination comprising a single center sill of a commercial shape extending longitudinally of said underframe along the median line thereof and having vertically spaced openings in its web, a cross bearer having upper and lower stress members extending through said openings, and means fixed to said stress members at opposite sides of said center sill web connected by rivets through said web.
19. In a car underframe, the combination

with a single flanged center sill disposed in the median line of said underframe, of a cross bearer comprising vertically spaced members, one of which extends through 5 said center sill, a longitudinal edge of one of said stress members being substantially in the vertical plane of the relatively opposite longitudinal edge of the other stress member, and angle sections disposed upon 10 opposite sides of said center sill being fixed

to said stress members and being fixed to said center sill by single rivets through said center sill.

In witness whereof I have hereunto set my hand in the presence of two witnesses. 15

HERBERT W. WOLFF.
